UNITED STATES PATENT OFFICE.

EUGENE SUNDERLAND HENRY AND DAVID B. CAMP, OF BOISE, IDAHO.

ELEVATING MEANS.

No. 826,164.

Specification of Letters Patent.

Patented July 17, 1906.

Application filed September 14, 1905. Serial No. 278,502.

To all whom it may concern:

Be it known that we, EUGENE SUNDERLAND HENRY and DAVID B. CAMP, citizens of the United States, residing at Boise, in the 5 county of Ada and State of Idaho, have invented a new and useful Elevating Means, of which the following is a specification.

This invention relates to means for elevating materials of various characters, and is 10 particularly useful for raising grain, water, and the like.

The object is to provide novel means of a simple nature for counterbalancing the weight of the material being raised, thereby 15 requiring less power to elevate the same a given distance.

The preferred embodiment of the invention is illustrated in the accompanying drawings, wherein—

20 Figure 1 is a side elevation of the elevating means. Fig. 2 is an end elevation thereof, portions being shown in section. Fig. 3 is a sectional view through one of the buckets, and Fig. 4 is a sectional view on the line 4 4 25 of Fig. 3.

Similar reference-numerals designate corresponding parts in all the figures of the drawings.

In the embodiment illustrated a suitable 30 supporting-frame 5 is employed, in which an endless elevator flight of buckets is mounted. This flight comprises a lower shaft 6 and an upper shaft 7, said shafts carrying sprocket-wheels 8, around which passes an endless 35 chain belt 9. Buckets 10 are mounted on the shaft, each bucket comprising side walls 11, a bottom 12, and a top 13, said top being tapered and having a closed end 14 and an open end 15. The open end forms a lateral 40 inlet and discharge, and the top constitutes a trough when the bucket is inverted.

A motor (shown conventionally at 16) is employed for driving the elevator and has a geared connection with the same. This connection includes a shaft 17, having a gear or belt wheel 18 mounted thereon, which wheel has a belt connection 19 with the drive-wheel 20 of the motor. Secured to one side of the wheel 18 are a plurality of buckets 21, forming the said wheel into a combined gear and motor wheel. The shaft 17 also is provided with a sprocket-wheel 22, about which passes a chain belt 23, that engages another sprocket-

wheel 24, mounted on the shaft 7. A receiver 25 is located at one side of the upper 55 end of the elevator flight, and extending therefrom is a spout 26, the discharge end of which is disposed over the buckets 21. A conveyer-trough 27 is located beneath the buckets and wheel 18. 60

In operation the motor 16 through the interposed gearing above described rotates the shaft 7, and thereby operates the endless flight. Consequently the material, whether liquid or solid, delivered to said flight will be 65 elevated in the bucket, and as said bucket turns to an inverted position at the upper end of the flight the contents will be discharged laterally into the receiver 25. From thence they will gravitate through the spout 70 26 and be delivered into the buckets 21 of the wheel 18, whereupon the material being elevated will be counterbalanced and said buckets 21 will discharge into the trough 27.

From the foregoing it is thought that the 75 construction, operation, and many advantages of the herein-described invention will be apparent to those skilled in the art without further description, and it will be understood that various changes in the size, shape, 80 proportion, and minor details of construction may be resorted to without departing from the spirit or sacrificing any of the advantages of the invention.

Having thus described our invention, what 85 we claim as new, and desire to secure by Letters Patent, is—

1. In elevating mechanism of the character described, the combination with an endless elevator flight, of a motor, gearing connecting the motor and flight, said gearing including a wheel having buckets, and means for delivering the material elevated by the flight to said buckets. 90

2. In elevating mechanism of the character described, the combination with an endless chain flight of buckets, of a motor, a shaft having a plurality of belt-wheels, a belt connection between one of the wheels and the flight, and a belt connection between the other wheel and the motor, a plurality of buckets mounted on one side of one of the wheels, a receiver for the material delivered by the flight, and a spout extending from the receiver and delivering to the buckets. 95 100 105

3. An endless elevator flight comprising a

chain and buckets mounted thereon, said buckets each having side walls, a bottom, and a tapering top, forming a trough when the bucket is inverted, one side of said bucket 5 being open to provide a lateral inlet and discharge for the bucket.

In testimony that we claim the foregoing

as our own we have hereto affixed our signatures in the presence of two witnesses.

EUGENE SUNDERLAND HENRY.
DAVID B. CAMP.
